UNITED STATES PATENT OFFICE.

JOSEPH F. CANADY, OF JERSEY CITY, NEW JERSEY.

APPARATUS FOR REGULATING COMBUSTION IN FURNACES.

1,102,718.

Specification of Letters Patent.

Patented July 7, 1914.

Application filed September 21, 1909. Serial No. 518,812.

To all whom it may concern:

Be it known that I, JOSEPH F. CANADY, a citizen of the United States, residing in Jersey City, county of Bergen, State of New Jersey, have invented a new and useful Apparatus for Regulating Combustion in Furnaces, of which the following is a specification.

This invention relates to a furnace regulating apparatus and more particularly to 10 that type wherein the pressure in the combustion chamber is maintained substantially constant and wherein any variation of pressure in the combustion chamber acts upon a regulating mechanism, which automatically 15 operates to restore the conditions within the furnace to normal.

In furnace regulating devices as heretofore constructed, the steam pressure has 20 been utilized to control both the escape of the products of combustion to the stack and the admission of the air from a suitable forced draft mechanism. The pressure in the combustion chamber is therefore controlled 25 indirectly by the steam pressure and it is possible to obtain quite a wide variance in pressure as compared to the air pressure in the boiler room.

In my present invention the air supply 30 to the combustion chamber is controlled directly by the pressure in said chamber and therefore any variation which may occur instantly affects the apparatus and either operates to reduce the pressure to normal or 35 raise the same, as the case may be. Furthermore, by my novel construction the steam pressure above a fixed maximum is utilized to operate an auxiliary control mechanism, whereby the pressure in the 40 combustion chamber is further regulated and acts upon the regulating apparatus, which is influenced thereby, to cut off or open the damper controlling the air supply.

For the purpose of illustrating my invention, I have shown in the accompanying drawings one form thereof which is at present preferred by me, since the same has been found in practice to give satisfactory and reliable results, although it is to be understood 45 that the various instrumentalities of which my invention consists can be variously arranged and organized and that my invention is not limited to the precise arrangement and organization of these instrumentalities as herein shown and described.

Figure 1 presents a side elevation of a steam boiler provided with an apparatus embodying my invention. Fig. 2 represents a section through one portion of my control apparatus. Fig. 3 represents an end elevation of the same. Fig. 4 represents a side elevation of the same. Fig. 5 represents a section through another portion of my control apparatus.

Similar numerals of reference indicate corresponding parts in the figures.

Referring to the drawings:—1 designates an ordinary type of boiler furnace, comprising a combustion chamber 2, ash pit 3 and 70 stack outlet 4 of any well known construction and forming no specific portion of my present invention.

5 designates a damper pivoted in any suitable manner on the stack 4, whereby the 75 passage of the products of combustion from the furnace to the stack may be controlled as desired. In the present instance a lever 6 is secured to the damper 5 and has mounted thereon a weight 7 for the purpose of 80 swinging the damper 5 in one direction while in the other direction it is operated by means of a rope 8 or equivalent means, which, as here shown, is controlled by an automatic controlling device 9. In the present 85 instance this device is adapted to be actuated by the steam pressure in the boiler and consists of a connecting rod 10 to which is secured the lever operating means 8, the said rope passing through the usual stuffing 90 box structure to the interior of the cylinder 11, wherein it terminates in a piston 12, against which the operating pressure is adapted to actuate and reciprocate the rod 10 in the required manner.

Ports 13 and 14 communicate respectively with opposite ends of the cylinder 11 in order to admit pressure alternately to each side of the piston 12 and they also communicate with chamber 15 having therein a 100 slide valve mechanism 16 which is connected by a rod 17 to an operating lever 18 suitably mounted on the casing 15. As here shown, the lever 18 is connected by a rod 19 to an arm 20, one end of which extends into 105 a diaphragm chamber 21, wherein it is mounted by means of knife edge constructions 22 and 23, whereby a pivot action is permitted, the movement of the bar 20 being controlled in one direction by a pressure 110 diaphragm 24 and in the opposite direction by a counterweight 25. Pressure is ad-

mitted beneath the diaphragm 24 by means of a port 26 to which it is led by means of a pipe 27, preferably connected to the steam outlet 28 of the boiler, although of course it may be led from any suitable portion of the steam head.

It will be apparent that by suitable adjustment of the counterweight 25 substantially any desired pressure may be exerted upon the diaphragm 24 which must be overcome by the steam pressure before the arm 20 will be raised and it will be seen that when the pressure in the boiler exceeds the pressure on the opposite side of the diaphragm 24, as determined by the counterweights 25, that the lever 20 will be raised and consequently shift the valve 16 so as to admit a suitable fluid pressure through the inlet 29 and by way of valve 16 to the port 13, whereupon the piston 12 is shifted to move the arm 10 to the right, as shown in Fig. 5. Of course it will be understood that when this connection is effected the port 14 will be thrown into communication with the exhaust port 31 of the chamber 15. This movement of the rod 10 pulls upon the connecting rope 8, whereupon the weight 7 is raised and the damper 5 closed so that the products of combustion cannot escape to the stack 4. Should, however, the pressure in the boiler now drop below that exerted on the diaphragm 24 by the arm 20, the rod 18 will be correspondingly lowered and the valve 16 brings the port 14 into communication with the inlet 29 and the port 13 in communication with the exhaust 31, whereby the piston 12 is shifted to the other end of the cylinder 11 and the connecting rod 10 forced to the left, as shown in Fig. 5, thus allowing the counterweight 7 to lower and open the damper 5.

The closing of the damper during the operation of the furnace will of course result in a raising of the pressure of the products of combustion in the combustion chamber, of which I take advantage and introduce a pressure control mechanism by which air passing through the burning fuel is accurately controlled. In the present instance this pressure control apparatus consists of a casing 32 secured at a suitable point to the boiler 1 and having an opening 33 in alignment with an aperture 34 communicating with the combustion chamber. The casing 32 is provided with air passages 35 leading to the interior thereof, between which and the opening 33 is suspended a plate 36 closely conforming to the interior of the casing 32 in order to prevent substantially any air passing through to the combustion chamber but at the same time permitting a free movement of the plate 36. As here shown, the plate 36 is secured at one end to a rod 37 passing through suitable bearings in the casing 32, whereby the plate 36

is pivoted and may swing freely within the casing 32.

It will be apparent if the pressure within the combustion chamber exceeds the atmospheric pressure that the plate 36 will take the position indicated in dotted lines in Fig. 2 and while in such position hold a rock bar 38 in position to operate parts hereinafter to be described. Should, however, the pressure in the combustion chamber drop below atmospheric pressure the plate 36 will swing and assume a position in full lines, Fig. 2, whereupon the rod 38 connected thereto will be shifted to its opposite operative position.

39 designates a valve casing suitably supported on the boiler 1 and in close proximity to the rod 38, which latter has secured thereto at one end, a valve operating rod 40 passing into the casing 39, having mounted thereon a slide valve 41 adapted to control an inlet port 42 and an exhaust port 43, whereby the fluid pressure admitted through the pipe 44 is controlled.

45 designates in the present instance, a cylinder suitably supported adjacent the valve chamber 39 and having therein a connecting rod 46 which is connected to the opposite end of the rod 38, whereby a dash pot structure is formed adapted to coöperate with the movement of the plate 36 to shift the valve rod 40 in one direction.

47 designates a cylinder suitably supported adjacent the casing 32 and having a pipe 48 communicating with the interior thereof at one end and connected to the inlet port 42, whereby fluid pressure may be admitted to the cylinder 47 and actuate a piston 49 secured to a rod 50 passing through a suitable stuffing box in the end of the cylinder 47 and connected to a rope 51 or like operating means, secured to a damper 52 controlling the admission of air to the ash pit 3.

53 designates an exhaust pipe leading from the cylinder 47 in order to relieve the pressure therein and permit the piston 49 to return to its normal position after its operation. It will be clear that if the rod 38 is operated by the plate 36 so as to bring the ports 42 and 44 into communication, that fluid pressure will be transmitted beneath the piston 49 in the cylinder 47 and raise the same, whereby the damper 52 is closed, and prevents a flow of air through the passage 54. This movement takes place whenever the pressure in the combustion chamber is above that of the outside atmosphere and it is desired to prevent any further air being operated to promote combustion in the chamber 2. As soon, however, as the pressure in the combustion chamber 2 drops, the plate 36 swings again so as to move the rod 38 to shift the valve 41 so as to throw the ports 43 and 44 into communication, whereby the pressure beneath the

piston 49 is relieved and the counterweight 55 on the damper regulating rod 51 returns the parts and opens the damper 52.

The operation of the device is as follows:—In operation the automatic damper regulator is adjusted to the required pressure by means of the counterweight 25 and the damper set in open position to be controlled by the regulator, as required. Air is supplied from a blower 60 or other suitable means to the passage 54, the damper 52 of course being open to permit the air to pass into the ash pit and promote combustion in the chamber 2. The pressure in the combustion chamber 2 is at this time substantially the same as that of the atmosphere or the pressure of the boiler room and the plate 36 is therefore hanging as indicated in full lines in Fig. 2 so as to maintain the valves controlling the chamber 52 in normal position, that is with the damper 52 open. As the steam pressure rises a pressure is sooner or later reached at which the action of the counterweight 25 is overcome and the bar 20 through the upward movement of the diaphragm 24 is raised to shift lever 18 and actuate the valve 16 to admit pressure to the cylinder 11. As soon as this takes place the damper 5 is actuated as before described and swings to closed position. Of course the closing of this damper has the effect of choking back the products of combustion which are still being added to by air forced through the passage 54 and soon a pressure is reached greater than the atmospheric pressure and the plate 36 is moved to the position indicated in dotted lines Fig. 2 and thereby brings the valve structure 39 into operation and admits pressure to the cylinder 47, whereupon the air damper 52 is dropped and the supply of air cut off. This action cuts off the supply of air to the combustion chamber and the pressure is lowered, whereupon the plate 36 swings back to normal position, opening up the air supply and as the steam pressure has in the meantime dropped the automatic damper control also comes into operation and opens the damper to the stack 4.

It will now be apparent that I have devised a novel construction of a furnace regu-

lator whereby the pressure in the combustion chamber operates directly to control the air supplied thereto and wherein a pivoted member maintained in normal position by gravity and subjected to the pressure of the combustion chamber on one side and on the other to the constant pressure of the atmosphere comprises a part of the complete unitary structure producing the result desired.

In so far as I am aware I am the first in the art to employ in a device of the character hereinbefore described, a controlling device governed by the steam pressure of the boiler and operating to cause a variation in the pressure, existing in the combustion chamber, whereby a secondary apparatus consisting of a pivot member, operates directly to control the supply of air promoting combustion.

It will now be apparent that I have devised a novel and useful construction which embodies the features of advantage enumerated as desirable in the statement of the invention and the above description and while I have in the present instance shown and described the preferred embodiment thereof which has been found in practice to give satisfactory and reliable results, it is to be understood that the same is susceptible of modification in various particulars without departing from the spirit or scope of the invention or sacrificing any of its advantages.

Having thus described my invention, what I claim as new and desire to secure by Letters Patent, is:—

The combination with a boiler and its furnace, of means for supplying air under pressure to the furnace, means controlled by the boiler pressure for regulating the discharge from the furnace of the products of combustion, and means controlled by the variations in furnace pressure for controlling the admission to the furnace of air from the air-supplying means in correspondence with the variations in the discharge of the products of combustion.
